(21) Appl. No.: **29/619,462**

The ornamental design for a heating module for a heat press, as shown and described.

DESCRIPTION

(22) Filed: **Sep. 29, 2017**

FIG. 1 is a perspective view showing my new design for a heating module for a heat press;

(51) **LOC (12) Cl.** **15-99**

FIG. 2 is a front elevation view thereof;

(52) **U.S. Cl.**

FIG. 3 is a rear elevation view thereof;

USPC **D15/146**

FIG. 4 is a left side elevation view thereof;

(58) **Field of Classification Search**

FIG. 5 is a right side elevation view thereof;

USPC D8/29.1; D10/83; D13/123, 133;

FIG. 6 is a top plan view thereof;

D15/122, 126, 128, 135, 136, 140, 144,

FIG. 7 is a bottom plan view thereof;

D15/144.1, 144.2, 146

FIG. 8 is a perspective view showing from the bottom thereof;

CPC A61K 36/37; A61K 36/185; B30B 9/047;

FIG. 9 is a perspective view showing the status of use; and,

B30B 15/34

FIG. 10 is a perspective view showing another status of use.

See application file for complete search history.

The broken lines in FIGS. 2 and 3 show portions of a heating module for a heat press that form no part of the claimed design.

The broken lines in FIGS. 9 and 10 are for the purpose of

showing environmental structure, and form no part of the claimed design.
